ATTORNEY.

UNITED STATES PATENT OFFICE.

SIDNEY M. HARVEY, OF DETROIT, MICHIGAN, ASSIGNOR TO ELECTRIC WELDING MACHINE COMPANY, OF DETROIT, MICHIGAN, A COPARTNERSHIP FIRM.

DESIGN FOR AN ELECTRIC-WELDER CABINET.

58,230.

Specification for Design. Patented June 28, 1921.

Application filed December 20, 1920. Serial No. 432,116. Term of patent 14 years.

To all whom it may concern:

Be it known that I, SIDNEY M. HARVEY, a citizen of the Dominion of Canada, residing at Detroit, in the county of Wayne and State of Michigan, have invented a new, original, and ornamental Design for an Electric-Welder Cabinet, of which the following is a specification, reference being had to the accompanying drawing, forming part thereof.

In the accompanying drawing a general

view in perspective clearly shows my ornamental design for an electric welder cabinet.

I claim:

The ornamental design for an electric welder cabinet as shown.

SIDNEY M. HARVEY.

Signed in the presence of—

B. F. WHEELER,
M. E. BROESAMLE.
